(57) CLAIM

The ornamental design for a bunk bed, as shown and described.

DESCRIPTION

FIG. 1 is a front, left perspective view of an example embodiment of a bunk bed of my new design;

FIG. 2 is a front, side view of the bunk bed of FIG. 1;

FIG. 3 is a rear, side view of the bunk bed of FIG. 1;

FIG. 4 is an end view of the bunk bed of FIG. 1; and,

FIG. 5 is top view of the bunk bed of FIG. 1.

The broken lines in the drawings illustrate portions of the bunk bed that form no part of the claimed design.
